JOSEF PEJCHAR, OF BROOKLYN, NEW YORK.

LOCKING DEVICE FOR PINS.

1,410,592.

Specification of Letters Patent. Patented Mar. 28, 1922.

Application filed March 24, 1920. Serial No. 368,408.

To all whom it may concern:

Be it known that I, JOSEF PEJCHAR, a citizen of the United States, and resident of the borough of Brooklyn, county of Kings, 5 city and State of New York, have invented certain new and useful Improvements in Securing and Locking Devices for the Pins of Brooches and other Articles, of which the following is a specification.

10 My present invention relates to means for securing and locking the pins of brooches and other articles of jewelry or the like. The object of my invention is to provide a device which may be applied readily to articles of different kinds, which will be strong, simple, and efficient to hold the pin in position, and which will be very compact so as to be applicable in conditions where but little space is available.

15 The particular means devised by me for carrying out this object will now be described in detail with reference to the accompanying drawings, and the features of novelty will then be pointed out in the appended claims.

20 In said drawings Fig. 1 is a perspective view of a brooch provided with my invention; Fig. 2 is an elevation of one form of the securing device or holder, in the open 30 position; Fig. 3 shows the same device in the closed position, with the pin in section; Fig. 4 is a section on line 4—4 of Fig. 2, and Figs. 5, 6, and 7, are sections on the lines 5—5, 6—6, and 7—7 respectively of Fig. 3; Fig. 35 8 is a view corresponding to Fig. 2 and showing a second form of my invention; Fig. 9 shows the same form as it appears when looking in the direction of the arrow in Fig. 8; Fig. 10 is a view similar to Fig. 40 3, showing a third form of my invention; Fig. 11 shows the same form as seen when looking in the direction of the arrow in Fig. 10; Figs. 12 and 13 are views, partly in section, illustrating a fourth form of my invention, in the open and the closed position 45 respectively; and Fig. 14 is a section on the line 14—14 of Fig. 12.

50 In each of the forms shown, the device comprises two parts, viz.: First, a holder proper adapted to be secured, say by soldering, to the base A or other suitable portion of the article to which the invention is to be applied, for instance a brooch, as in Fig. 1. Second, said device comprises a locking appliance connected with said holder movably

and adapted to lock in position, the pin B of the brooch or other article.

According to my invention, the holder is made from a tubular piece of metal 20, of uniform cross section, which may be circular (see Fig. 7), although cross sections of other shape might be employed. By cutting, sawing, stamping, or any other appropriate operation, I form in such tube 20, a socket 21 with a narrowed entrance 22 through which the pin B may pass. This entrance is adapted to be closed or cleared by the locking device connected movably with said tubular holder body. The tubular construction of this body, besides giving it great 70 strength, presents additional advantages as follows, irrespective of whether such body is used with or without a locking device: First, the end which is fitted to the base A can be cut off readily to any length required, 75 so that the socket 21 and its entrance 22 will be at the proper distance from the base A. Second, this end can be cut off straight, as in Figs. 2, 3, 4, 5, and 10 to 13 inclusive, or in any other manner as may be desirable to 80 properly fit the base A, for instance so as to give such end the stepped shape shown in Figs. 8 and 9. Third, the tubular bottom end or attaching end of the holder body can be changed in cross sectional shape easily by 85 compression or pinching, or otherwise, so as to conform to the shape of the base A, and particularly to the width of such base; for instance, if the tube is originally of circular cross section (as in Fig. 7), its attaching end 90 can be given readily a different cross section, say an oval one, by pressing this end with a pair of pliers.

The features described so far are shared in common by all the forms of my invention shown herein.

Referring now more particularly to the constructions shown in Figs. 1 to 11 inclusive, the invention comprises a sliding locking device movable in suitable parallel 100 tubular guides 23, 23' extending to the outer or free end of the holder body 20. In each of these cases the locking device is shown as comprising a U-shaped portion made of wire (preferably circular in cross section), 105 the parallel end members 24, 24' sliding in the guides 23, 23' respectively, with a fit which is sufficiently tight to prevent accidental movement of the locking device. The said device further comprises a plate 25, 110

generally of a shape corresponding to this end of the holder body (Fig. 6), but of greater size, so as to form a stop limiting the inward movement of the locking device.

- 5 The U-shaped wire portion extends through said plate 25, and the transverse member 26 of the wire is located on the outer or exposed side of the plate. The latter is connected with the wire rigidly (soldering may 10 be resorted to) and also forms a handle for the convenient manipulation of the locking device. The member 24 is adapted to close or clear the entrance 22, according as the locking device is in its inner or in its outer 15 position.

Different expedients may be employed to limit the outward movement of the sliding locking device of Figs. 1 to 11. For instance, in the construction illustrated by Figs. 1 to 7, 20 the member 24' (distant from the entrance 22) may have its end formed into a stop by bending it inwardly, that is to say, toward the closing member 24, as indicated at 27, to come in contact with the narrowed portion 25 28 of the body 20 when the locking device is brought to the outer or open position, Fig. 2. In this position, the hook or stop 27 is received within a recess or socket 28'. In order that this construction may be assembled, the steps of its manufacture are as 30 follows: While the body 20 is still of uniform (say, circular) cross section from end to end, the completed locking device is inserted at the outer end of said body, and 35 then said outer end is compressed or pinched so as to form the contraction 28 and the socket 28', as well as the two parallel tubular guides 23, 23', it being understood that at that time the stop 27 is between said contraction 28 and the base A. Of course, I 40 might first form the contraction 28, socket 28', and guides 23, 23', and then insert the locking device in an unfinished condition, with both members 24, 24' straight to their 45 very ends, the lower end of the member 24' being bent subsequently to form the stop 27; but this operation is not so convenient as the one just described.

According to Figs. 8 and 9, the stop 27' 50 is formed by bending the lower end of the member 24' outwardly and projecting it through a longitudinal guide and limiting slot 29.

Figs. 10 and 11 show the stop 27'' formed 55 by an outward bend at the lower or free end of the closing member 24, and preferably the guide tube or sleeve 23 is formed with a recess 23'' in which said stop finds lodgment when the locking device is in its outer 60 or released position, so that this stop will not form an obstruction on which the pin B might catch as it swings (on its pivot B') into the socket 21.

The operation of these forms of my invention will be understood readily. By

using the plate 25 as a handle, the person can either pull the locking device out to the open or releasing position (Figs. 2, 4, 8, and 9), or push it in to the closed position (Figs. 3, 5, 10, and 11), the friction between the members 24, 24' and the guide sleeves 23, 23' being sufficient to hold the locking device against accidental motion, in either position.

In Figs. 12, 13, and 14 the parts 20, 21, and 75 22 are substantially the same as described above (except that the tubular body 20 is shown compressed to a form which is oval and almost flat in cross section, see Fig. 14), but instead of the sliding lock, I have shown 80 a locking device or lever 30, 31 pivoted to the holder body 20 about an axis 32 transverse to the length of said body. The arm 30 of the lever forms a handle for operating the locking device, while the arm 31, when 85 swung into the position Fig. 12, leaves the entrance 22 open to admit the pin B, whereupon said arm is brought to the locking position, Fig. 13, in which it engages the inner surface of the tube 20, being 90 stopped thereby. In this construction also, friction is relied upon to prevent accidental movement of the locking device.

I claim as my invention:

1. An article provided with a base and a 95 pin connected therewith movably, and a tubular holder for the free end of said pin, said holder being secured to said base and having its axis at an angle to the base, and being provided with a lateral opening for 100 the passage of said pin and a locking member movable in said tubular holder to close or clear said opening.

2. A holder for the pins of brooches and other articles, comprising a tubular body 105 having an opening at one side for the passage of said pin, and a continuous annular wall both above and below said opening.

3. An article provided with a base and a pin connected therewith movably, a tubular holder one end of which is secured to said base, the axis of said holder being at an angle to the base, said holder having a lateral opening for the passage of the free end of said pin, and a continuous annular wall 115 between the base and the adjacent side of said opening, as well as a continuous annular wall on the opposite side of said opening, and a locking member contained in said tubular holder and movable to close or clear 120 the said opening.

4. A holder for the pins of brooches and other articles, comprising a body having a lateral opening for the passage of said pin, and two parallel longitudinal guides located 125 at the free end of the body, and a locking device having parallel members mounted to slide in said guides and one of them controlling said lateral opening.

5. A holder for the pins of brooches and 130

other articles, comprising a body having a lateral opening for the passage of said pin and two parallel longitudinal guides located at the free end of said body, and a locking device having parallel members mounted to slide in said guides and one of them controlling said lateral opening, and one of said members being formed with a stop projection to limit the movement of the locking device.

6. A holder for the pins of brooches and other articles, comprising a body having a lateral opening for the passage of said pin and two parallel longitudinal guides located at the free end of said body, and a locking device having parallel members mounted to slide in said guides and one of them controlling said lateral opening, and a trans-

verse member connecting said parallel members and forming a handle for operating said locking device and also forming a stop to limit the inward movement of said locking device.

7. A holder for the pins of brooches and other articles, comprising a body having a lateral opening for the passage of said pin and two parallel longitudinal tubular guides located at the free end of said body, and a locking device having two parallel members fitted into said tubular guides and one of said members controlling said lateral openings, said locking device having a limited sliding movement lengthwise of said body.

In testimony whereof I have signed this specification,

JOSEF PEJCHAR.
